[57] CLAIM

The ornamental design for a carrying case for portable
telephone, as shown and described.

DESCRIPTION

FIG. 1 is a perspective view of a carrying case for
portable telephone, showing my new design;

FIG. 2 is a front elevational view;

FIG. 3 is a rear elevational view;

FIG. 4 is a top plan view;

FIG. 5 is a bottom plan view;

FIG. 6 is a left side elevational view; and,

FIG. 7 is a right side elevational view.

The carrying strap has been broken away in FIGS. 2, 3,
6 and 7 for the convenience of illustration.

FIG. 1

FIG. 2

FIG. 4

FIG. 5

FIG. 6

FIG. 7
